Specification of Letters Patent. Patented June 9, 1914.

Application filed September 12, 1910. Serial No. 581,521.

To all whom it may concern:

Be it known that we, ALBERT D. PEJAUO and JOHN J. ZEITZ, citizens of the United States, residing at Cleveland, in the county of Cuyahoga and State of Ohio, and Warren, in the county of Trumbull and State of Ohio, respectively, have invented certain new and useful Improvements in Paper-Folding Machines, of which the following is

10 a specification.

Our invention relates to folding machines, and is an improvement in the machine bearing Patent No. 872,469, and dated October 11, 1910, and the improvement consists in 15 the new construction and arrangement of parts substantially as herein shown and described and more particularly pointed out in the claims.

As improved, this machine will produce 20 a multitude of different folds in sheets of paper of varying sizes and thicknesses by simple and convenient changes or adjustments in the machine, and the sheets will be folded absolutely true and accurately at 25 a rapid speed regardless of the size or thickness of the paper or the number of folds made therein.

In construction, the machine is particularly designed to eliminate static electricity 30 so as to avoid check and inaccuracy in feeding and folding operations, and the parts are particularly arranged and constructed to give an open view and convenient accessibility to the interior, especially along the 35 line of travel of the paper.

Finally, the machine embodies stacking means to coöperate with the adjustable folding means and which stacking means is also adjustable and particularly positioned in 40 relation to the adjustable folding means so as to permit stacking of all of the different kinds of folded sheets adapted to be produced by this machine.

Other objects are also hereinafter described.

In the accompanying drawings, Figure 1 is a plan view of the improved machine. Figs. 2 to 7 inclusive are diagrammatic views on a reduced scale of six sheets of 50 paper with different fold lines as adapted to be produced by this machine. Thus, Fig. 2 illustrates a single fold to produce what is commonly known in the printers' art as a four-page sheet. Fig. 3 represents two folds

at right angles to produce an eight page sheet. Fig. 4 shows two right angle folds to make a twelve-page sheet, and Fig. 5 shows three parallel folds and one right angle fold to make a sixteen page sheet. Figs. 6 and 7 show six-page and eight-page sheets, respectively, as produced by parallel folds alone. Fig. 8 is a side elevation of the complete machine with the fly-wheel of the machine removed and the frame partly broken away to more clearly disclose the interior construction, and Fig. 9 is a side elevation of the opposite side of the machine. Fig. 10 is a perspective view of the sectional cam disk used to time initial feeding operations for the paper sheets. Fig. 11 is an end elevation of the complete machine looking in from the feed side of the machine, and Fig. 12 is an end elevation looking in at the stacker side of the machine. Fig. 13 is a sectional view centrally and vertically 75 through the machine on line 13—13, Fig. 12. Fig. 14 is a sectional view on vertical line 14—14 of Fig. 13. Fig. 15 is a sectional view on vertical line 15—15, Fig. 14. Fig. 16 is a sectional detail enlarged of one of 80 the laterally adjustable rack rollers on its supporting shaft. Fig. 17 is a sectional view in plan on an irregular line horizontally at the top of the machine immediately below the top plate thereof. Fig. 18 is an enlarged 85 sectional detail of the cam for actuating the third folding blade. Fig. 19 is a sectional view in plan on horizontal line 19—19, Fig. 13. Fig. 20 is an enlarged cross sectional view of a portion of the slotted center plate 90 and showing the rotary frame and creasing rolls and parts carried thereby in set position to deflect a folded sheet of paper without making a third fold therein. Fig. 21 is an enlarged plan and sectional view of one of 95 the stackers, disclosing also the rotatable frame which carries the creasing and delivery rolls in one of its working positions in relation thereto. Fig. 22 is a sectional view and side elevation on line 22—22, Fig. 21. 100 Fig. 23 is a sectional view similar to Fig. 13 but showing the second and third folding mechanisms as rotarily shifted to operatively align with the horizontal slot in the center plate instead of the vertical slot. 105 Fig. 24 is a detail sectional view of a portion of the central slotted plate showing a deflector plate for shunting a single folded

sheet direct to the creasing rolls and the stackers.

The main frame of the machine consists of open side pieces 2 united by top plates 3 5 and a central cross wall or plate 4 vertically arranged beneath the same, and the top is divided by a slot 5 parallel with and at one side of central plate 4, which also is slotted from front to rear by a pair of slots 6 and 7, 10 respectively, which bisect each other at right angles. The first fold in a sheet of paper is produced by vertically reciprocating blade 8 operating in slot 5, and the second fold of the sheet is made by a horizontally reciprocating blade 9 which operates in either one of the two slots 6 or 7 in central plate 4.

The initial feed.—The paper sheet is fed beneath the first folding blade 8 by a pair of rollers 10 and 11 located above and below 20 top-plate 3, respectively, in advance of said blade, roll 10 being supported by an oscillating frame 12 pivotally secured to standards 13 which slidably confine support 14 for blade 8 at its ends. Frame 12 has a 25 pending arm (see Fig. 9) with a roller at its end which has riding engagement with a sectional disk cam 16 (see Fig. 10) whereby said frame and roller 10 is raised at timed intervals to discontinue forward feed 30 of the paper and to release grip upon the same when the first folding blade 8 is in operation. Three cam disks are shown as rotatably adjustable in respect to each other to shorten or lengthen the duration of feed- 35 ing operation according to varying lengths of paper or the position of the first fold to be made therein. In feeding the paper to roller 10 a pair of laterally adjustable guides 17 on plate 3 determine its position relatively to a longitudinal center line C—C, 40 Fig. 1. Guides 17 slide in cross grooves or slots 18 in the top face of plate 3 and these grooves are beveled or inclined upwardly as shown in Fig. 13 to prevent any impediment or check in feeding the paper. The 45 paper sheet is further guided into or beneath roll 10 by a hooded deflector 19 on oscillating frame 12. In operation, the sheet is then forcibly fed over the top plate and beneath blade 8 until it engages a stop-gage 50 adjustably secured to the top plate in any predetermined set position thereon as provided for by thumbscrew 21 and numerous screw openings 22. Suitable side guides 23 55 having fastening thumbnuts 24 may also be used to keep the paper in straight alignment after passing blade 8. Obviously any other guide and stop adjustment may be used. However, when the paper sheet strikes stop 60 gage 20 it is essential that the paper shall not rebound or have a return movement, otherwise absolute accuracy in producing the first fold cannot always be obtained. Therefore, roll 10 is not lifted until folding 65 blade 8 comes into action, but in the mean-

time roller 11 necessarily revolves, and as it is practically impossible to time the action of these parts without causing a buckle in the paper, a cross-bar 25 is used to bridge the paper at one side of blade 8 which prevents buckling of the paper at this side of the blade. In addition, plate 3 is formed with a swell or rounded rib 26 paralleling blade 8 at a point intermediate roll 10 and the blade, which positively produces a buckle in the paper at this point to take care of any surplus in the paper feed and in order to be assured that the paper will always abut against stop-gage 20. Then to assure feed of paper beneath blade 8, a deflector plate 27 is placed above rounded rib 26, see Fig. 13.

The first fold.—Folding blade 8 has a relatively short intermittent travel timed to cooperate with the raising and lowering of feed roller 10 and other working parts of the machine as hereinafter more particularly described. Only a short movement of blade 8 is required to carry the paper through slot 5 to produce and determine the first fold as this operation immediately carries the folded portion of the sheet into the bite of a pair of rollers 28—28' located beneath plate 3 on either side of slot 5. One of said rollers is mounted in slideable bearings or boxes which are spring pressed, whereby paper of varying thicknesses may be permitted to pass between the rollers and to be folded or creased thereby, but creasing or ironing out of the fold is not the only function of these rollers as they also act as feed rollers to carry the folded sheet downwardly between a series of rollers 30 and a series of rolls 31 located in openings in plate 4. However these separate series of rollers do not grip the sheets but are about one thirty-second of an inch apart as their function is to merely assure an uninterrupted feed downwardly until the sheet is halted by suitable gage-stops 32. Said gage-stops determine the distance to which the sheet will be fed below horizontal slot 7 and adjustments thereof are made by bolts and nuts 33 slideably confined in vertical slots 34 in plate, see Fig. 14. Two gage-stops 32 are used, one at either side of the central vertical slot 6 in the plate 4, and as a further precaution two or more paper retainers 35 are detachably mounted thereon to hold the paper sheet flat against plate 4. These retainers may be adjusted both vertically and laterally upon said gage stops by means of thumbnuts 36 adapted to pass through longitudinal slots in the retainers and screw into any one of the numerous screw openings 37 in the gage-stops, see Fig. 14.

Paper positioning parts.—Now, it will be noted that vertical slot 6 in plate 4 is located centrally between the ends of folding blade 8, and that paper guides 17 on the top

plate may be set to feed paper of any width centrally in respect to said slot or to any distance at either side thereof as may be predetermined. This permits various kinds of folds to be made and particularly when a third fold is produced subsequently. This is referred to at this time for the reason that guides 17 are not alone depended upon for guiding and alining the paper sheet 10 relatively to vertical slot 6 as a second pair of guide and gage strips 38 and 39, respectively, are also used. These strips are vertically mounted on the face of cross plate 4 between rolls 31 and roller frames 40 which 15 carry rollers 30. Guide and gage strip 38 is laterally adjustable at the right of vertical slot 6; see Fig. 14, a thumb and lock nut 41 being used and adapted to be slidably confined in cross slot 42 in plate 4. When adjusted this plate 38 is fixed parallelly to vertical slot 6 and becomes a fixed guide and stop for the paper at one edge and positively determines the position of the folded sheet in making the second fold. This is 20 material as it is customary in printing shops to cut only two edges of the paper accurately square or at right angles to gage or set the sheets in the printing press when printing. Often, paper has a so-called deckel edge, and 25 again, paper is cut very imperfectly in size and width particularly when large jobs are in hand. These conditions must be met in a folding machine, otherwise the paper sheets will often be confined or engaged too 30 closely at their edges and stick or choke up a machine in their passage therethrough. In the present instance strip 38 is always fixed in any of its adjusted positions to engage the cut edge of the paper and strip 39 35 is made not only laterally adjustable but also laterally reciprocable to produce a so-called jogger which will jog or move the sheet to the right and into contact with strip 38, thus alining and positioning each 40 and every sheet in respect to vertical slot 6 as it passes through the machine and prior to making the second fold.

The means for supporting and operating jogger strip 39 consists in a longitudinally 45 movable rod 43 journaled to reciprocably slide within limits in plate 4, said strip 39 being adjustably secured on rod 43 by a thumbnut 44. One end of rod 43 projects beyond side 2 of the main frame and has a 50 coiled spring 45 about the same engaging an end collar thereon to normally hold the parts outward against the rounded arm end of bell-crank 46 which is operatively engaged by cam 47 on countershaft 48, see 55 Fig. 14.

Roller frames 40.—Two such frames are shown as pivotally suspended from a cross shaft 50,—one at either side of slot 6 to permit folding blade 9 to enter said slot without interference. Each frame 40 lies par-

allel with plate 4 but apart therefrom, and is locked to the main frame by a pin 51 passing through sides 2. Withdrawal of pin 51 permits either roller frame 40 to be bodily lifted or swung upwardly to an inclined 70 position away from plate 4 (see Fig. 15) and this is a material advantage when access is desired behind the roller frame to make adjustments or changes or to remove paper when choked in the machine. Each roller 75 30 is slidably mounted upon cross shafts 52 journaled in each frame 40, a spring wire key 53 being used to slide in the spline or groove 54 of the shaft and hold the roller 30 frictionally in any adjusted position, see 80 Fig. 16. Lateral adjustment and set position of the rollers is determined by the width of the paper, or the relatively different positions the paper sheet may assume to central slot 6 in making a right angle fold. 85 Each roller shaft 52 has a gear 55 at its outer end (see Fig. 8) which meshes with an intermediate idler pinion 56, said gears and pinions being mounted on the outer bar of each frame and giving a continuous train 90 of gears to rotate all the shafts 52 at the same speed, power being derived from pinions or gears 57 rotating freely upon cross shaft 50 and meshing with gears 58 on roller 28 directly above the roller frames. 95 Roller 28 is driven in turn by small pinion 59 meshing with a large gear 60 mounted to rotate freely at the outside of the main frame (see Figs. 9 and 14) on short shaft 61, and said gear is integral with or rigidly 100 secured to bevel gear 62 which meshes with a like gear 63 on countershaft 48. The cam disks 16 are mounted upon and driven by this gear 60. Gears 55 also mesh with pinions 65 of rolls 31 and rotate the same 105 reversely to rollers 30, whereby a folded sheet is positively directed downward regardless of any spreading action of its folds, this being the natural tendency of nearly all sheets when folded, particularly in thick 110 or heavy papers.

The second fold.—Now assuming that the second folding blade 9 is set in the vertical position shown in Fig. 13, a second fold in the sheet can then be made at right angles 115 to a fold made previously by blade 8. This is done by a forward movement of blade 9 through the medium of an oscillating gear segment 66 rotatably mounted on cross shaft 67 and controlled by a cam 68 on rotatable cross shaft 69, said segment meshing with rack sleeve 70 fixed by set-screw 71 to short shaft 72 of forked blade support 73. Sleeve 70 is slidably supported within cross bracket 74 which forms a rigid part of the main 120 frame between its sides 2, and a coiled spring 75 bearing against both said bracket and an enlargement on sleeve 70 serves to retire the blade and also maintains working contact between segment roller 76 and cam 125 77.

68. However, blade support 73 is sufficiently spaced apart from the end of sleeve 70 to permit an independent longitudinal movement of the blade and its shaft in respect 5 to said sleeve when set-screw 71 is released and blade 9 rotated. Otherwise roller frames 40 would obstruct and prevent such rotation, but as arranged and constructed clearance may be had for the blade. No off- 10 sets or lugs are on the inside bar of the rack frame 40, the ones seen in dotted lines Fig. 13 being on the outside bars to support the intermediate gears 56, and therefore out of range of the radial sweep of blade 9. A 15 knurled finger or hand hold 77 on shaft 72 serves to shift and rotate blade 9 temporarily but if the blade is to be withheld from active reciprocation in either slot 6 or 7, set screw 71 may be used to fasten shaft 20 72 in any changed or adjusted position within sleeve 70.

Operation of the second folding blade 9 is necessarily timed with that of the first folding blade 8, and to this end shaft 69 is 25 driven by a train of gears and pinions 78, 79, 80 and 81 mounted at one side of the main frame and operated by an electric motor 82, belt 83, and pulleys 84 and 85, respectively. Bevel gears 86 and 87 on cross 30 shaft 69 and countershaft 48 respectively, convey power to said countershaft and therethrough to the first folding blade 8 by means of cam 88 on said countershaft and bell-crank 89 on rock shaft 90 journaled in 35 sides 2 of the machine. However to complete the connections rock shaft 90 also has a bifurcated arm 91 which corresponds with the bifurcated arm of bell-crank 89, and links 92 at either side of the machine connect 40 said arms with the ends of blade supports 14. A coiled spring 93 on rock shaft 90 engages therewith and with the frame to always return blade 8 to an elevated position and serves also to keep roller 94 of the 45 bell-crank in working engagement with cam 88.

Final second-fold steps.—The action of blade 9 in making a second fold is not merely confined to forcing the sheet of paper 50 through either slot 6 or 7, but also contemplates the carrying of the folded sheet into the bite of a pair of rollers 95 and 96 which may be termed either feed or creasing rollers or even ironing rolls. These rollers are 55 rotatably mounted in close adjuxta position to central plate 4, a rotatable carrying frame 97 being used for this purpose in which trunnion 97 represents the rotary axis thereof. This axis is coincident with the 60 axis of rotatable blade 9 so that both said members may be rotated and set correspondingly to permit co-action of the parts in folding, feeding, creasing and stacking operations. A locking pin 99 carried by depending arm 100 is adapted to enter either

of several openings 98 in frame 97 to lock the same in either of three adjusted positions, whereby final delivery of the folded product may be either to the right or to the left, or below the axial line of rotation. 70

The third fold.—Five rollers in all are mounted on rotatable frame 97, the first rollers 95 and 96 as described serving as receiving and feed rollers for the folded sheet, and the other three, represented by 101, 102 75 and 103, respectively, being more properly creasing or ironing rollers to more completely finish the folds whether one or more in number. To this end also, roller 101 contacts with roller 96, but its axial center is 80 located relatively behind and beneath the feed roller 95 (see Figs. 19 and 20) to permit a third fold to be made by a third folding blade 104 which is reciprocably mounted in line with the bite between rollers 96 and 85 101 and has a movement in a plane at right angles to the plane of the sheet as fed forward by rollers 95 and 96. Rollers 102 and 103 are paired to work together to receive the sheet from the bite of rollers 96 and 101, 90 and although in effect also creasing or ironing rollers the same may also be termed discharge rollers for the finished sheet as it is from this point that the folded product is finally delivered to either or both stackers 95 105 and 106, respectively, and as will herein-after more fully appear.

In making a third fold, the sheet first enters a chute or narrow passage formed by a pair of plates 107 secured to rotary frame 100 97, the mouth of the chute being directly opposite the bite line of rollers 95 and 96, but with folding blade 104 located intermediate. An adjustable gage-stop 108 mounted on one of the plates 107 limits the outward movement of the paper as may be predetermined, and when thus checked in its travel the tendency of the sheet is to buckle where unconfined owing to the continuing forced feed produced by rollers 95 and 96. 105 However such buckling is purposely desired within limits as the sheet must be held against gage-stop 108 to permit accurate folding on predetermined lines, and then blade 104 comes into action immediately. 110 This blade has a curved tucking face and straight edge to fold and carry the sheet into the bite of rollers 96 and 101.

The paper deflector.—Blade 104 is also provided with an adjustable plate 109 having a curved deflector 110 adapted to be permanently retired during third folding operations see Fig. 19. Otherwise interference with a free buckling of the paper is apt to occur in three-fold operations and 120 which manifests itself in a wrinkled and imperfectly folded product. However, a deflector is needed when blade 104 is operatively disconnected and as occurs when only a single or double fold is wanted, and the 130

relation of the parts is then as shown in Fig. 20. Here blade 104 is assumed to be stationary and fixed to lie across the path of the sheet as fed forward by rollers 95 and 96, thus cutting off entrance into chute 107, and deflector 110 is also advanced or set to bring its curved surface in the plane of travel of the paper to shunt it at right angles into the bite of rollers 96 and 101.

10 *Drive parts.*—The operating connections for the rollers and the third folding blade on rotary frame 97 comprises a cross shaft 111 journaled at the top of the machine at one end thereof and driven by bevel gearing 112 at one end of countershaft 48. A swinging cross-head 113 is suspended from shaft 111 between sides 2 of the machine, and trunnion 97' of rotary frame 97 is journaled in depending arm 100 of said cross head 113.

15 A short vertical shaft 114 at one side of arm 100 and bevel gearing 115 at the top thereof communicate power from shaft 111 to bevel gears 116 at short horizontal shaft 117 arranged centrally through trunnion 97', and bevel gearing 118 extend the line of power connections to shaft 119 within frame 97. This arrangement permits rotation of frame 97 on its axis and gives constant power connections in all changed positions thereof.

20 Now proceeding to trace the power connections for the feed and creasing rollers carried by rotary frame 97, one train of gears 120 leads from one end of shaft 119 to rollers 101, 96 and 95 in the order named, see dotted lines Fig. 21, and a second train of gears 121 at the other end of frame 97 leads from shaft 122 of roller 101 to the shafts of discharge rollers 102 and 103, thus 25 completing the power connections for all the feed and creasing rollers on frame 97.

30 *Third folding blade details.*—This blade is intermittent in operation and may be disconnected so as to be entirely inoperative.

35 Thus, slideable supports 123 for blade 104 occupy the slotted ends of frame 97 and are connected by links 124 with the free ends of a pair of arms 125 secured to the opposite ends of an oscillating shaft 126 journaled 40 in the ends of frame 97, see Figs. 17 and 9. Oscillation is imparted to shaft 126 by an arm thereon having a roller 127 adapted to ride against cam 128 sleeved on power shaft 119, a spring 129 connected with said arm 45 and the end of frame 97 serving to maintain operative engagement. Cam 128 has a serrated or toothed hub 130 (see Fig. 18) adapted to interlock with a serrated collar 131 fixed to shaft 119, and a lift spring 132 50 mounted in a recess between the serrated parts tends to separate the same. However a thumbnut 132' holds the cam interlocked with collar 131 when blade 104 is to remain in action. When released and the cam independently rotated to permit roller 127 to

rest upon the low point of the cam, the blade assumes the position shown in Fig. 20 to deflect the sheet into the creasing rollers without further folding.

55 *Adjustments.*—When producing two or more folds, particularly right angle folds, great difficulty is experienced in accurately alining the edges and in preventing overlap thereat on diverging lines. This is greater or less according to the kind of material being folded. Thus, if a sheet of paper is given one fold and then presented edgewise as folded into the bite of two rollers to make a right angle fold, a greater resistance is offered at its folded corner than where free and separated. Consequently folding blade 9 which makes the second fold is made adjustable to advance the folded corner when this is found necessary, and to this end blade 9 is preferably hinged at one end by a pivot pin 133 to its support 73 and is further fastened by a bolt and slotted connection 134 between ears 135 at the opposite end of said support. An adjusting screw 136 in support 73 bears against the edge of blade 9 to adjustably change the relative working angle of the front edge of said blade in respect to plate 4 and its slots, and as intimated, so that the bottom or folded edge of the sheets may be projected through the slots and into the bite of rollers 95 and 96 in advance of the other portion of the sheet. A somewhat similar adjustment or change in working relations in respect to blade 9 and plate 4 is obtained in the parts carried by rotary frame 97 by reason of an adjustable eccentric connection 135' which serves to support the free end of swinging cross head 113 upon the main frame. This eccentric connection comprises a bolt 136' passing through a rotatable barrel 137 located at either side of the machine in sides 2 thereof and where convenient slideable engagement is made with the slotted ends of inwardly extending arms 138 of cross head 113. Bolt 136' is off center in the barrel, and a knurled collar or head 139 gives a handhole to rotate barrel 137 when set screw 140, which serves to lock it in any adjusted position is released, see Figs. 1, 14 and 17. Only slight rotation of both barrels 137 is needed to make an appreciable change in angle from the vertical position of frame 97 relatively to plate 4.

100 *Accessibility.*—Removal of bolts 136' from barrels 137 also permits cross-head 113 and the frame 97 carried thereby to swing on cross shaft 111 without disturbing eccentric adjustments and such swinging of the parts away from plate 4 gives convenient access to rollers 31 and other parts within the frame to oil or clean them and also to permit removal of any sheets of paper caught or choked at this point. Top plate 3 is also removable and when this is 105

110 115 120 125 130

done cross-head 113 may be swung into a position entirely above the machine where every part on rotatable frame 97 may be conveniently inspected, cleaned, adjusted or repaired.

To eliminate feed trouble due to static electricity many parts of the machine are made of aluminum. Thus, top plate 3 is made of this material to prevent charging of the paper with static electricity at the outset. Roller 28 is also made of aluminum, the other roller 28' being preferably of rubber or rubber covered. Again, all rolls 31 and rollers 30 are made of aluminum. If made of other material, say steel, and spaced apart as shown, the sheet of paper has a tendency to curl in the direction of rotation of the roll and wind about the same. As gravity is also largely depended upon to feed the paper sheets downward after leaving rolls 28, 28', plate 4 is also made of aluminum to avoid clinging of the sheets thereto when charged with static electricity. The feed and creasing rollers carried by rotatable frame 97 are made of steel and provided with knurled paper-engaging surfaces, and are not necessarily made of aluminum as the paper sheets are always gripped between them during feeding and creasing operations. Roller 95 is annularly grooved at regular distances to permit the deflector portions of plate 109 to pass the roller without interference. Rollers 95, 96 and 102 have their shafts mounted in slideable spring pressed boxes 141 to give uniform gripping effects on the paper sheets and to permit different thicknesses of sheets to be fed without trouble.

The stackers.—One of the material improvements in this machine is embodied in the stacking mechanism for the folded product and which mechanism is particularly constructed to coöperate with the discharge rollers in the rotarily adjustable frame 97 regardless of their variously set positions and the width, length or kind of folded sheet produced. Viewed from one end (Fig. 12) two independent stacking devices 105 and 106, respectively, stand closely adjacent to rotatable frame 97, one at either side within the sides 2 of the main frame. As both are identical in construction and are operated alike, the same reference letters will be applied to corresponding parts in describing the same. Thus, each stacker comprises a right angled table 142 having a dove-tailed channeled portion 143 adapted to support the same for vertical adjustment on the inset guide ribs 144 on sides 2. Lowering of the tables allows free rotation of frame 97, and set screws 145 fasten them at any elevation. In Fig. 12 the stacker table at the left is shown as elevated ready for use, and the stacker table at the right is down and not suitably positioned for use, discharge of the

finished product being to the left instead of to the right. However, this order is often reversed, dependent upon the original positioning of the paper in respect to the longitudinal center of the machine, or the kind of fold being made, or to any advantage of light or other natural conditions about the machine which will aid working thereof.

Stacker drive parts.—Constant operation of the stackers is obtained by power connection with countershaft 48, bevel gears 146 transmitting rotation to vertical shaft 147 at one side of the machine and which shaft 147 drives a cross shaft 148 at the bottom by bevel gears 149. This shaft in turn operates two short shafts 150 supported in bearings 151 on sides 2, bevel gears 152 being again used to communicate power thereto. Shafts 150 are sleeved and rotate within a rigid arm 153 fixed on each table 142, and each shaft has a cam 154 splined to slide lengthwise thereon as tables 142 are raised or lowered. Each cam 154 engages a roller 155 on the short arm of oscillating gear segment 156 secured to the bottom of table 142. A pinion 157 and quadrant gear 158 reciprocably operates a rack bar 159 at the bottom of each table on each actuation of segment 156 and a coil spring sleeved upon bar 159 and engaging a collar affixed thereto returns said parts to normal set position as shown in Fig. 21. A cross yoke or bar 161 is attached to one end of bar 159 and has vertically standing lugs 162 which project through open slots 163 in the table and wherein they are adapted to reciprocate upon reciprocation of bar 159. A channeled push-plate 164 extends transversely across the top of each table 142 and is adjustably supported by downwardly extending stems 165 sleeved in lugs 162 and secured at any suitable elevation by set screws 166, see Figs. 8 and 21. The folded sheets are successively discharged from rollers 102 and 103 in line with and at the front of push-plate 164 and each sheet is bodily shoved forward on the table upon the forward movement of the push-plate as brought about by cam 154 and its associated mechanism. When the folded sheet is thus banked with the other folded sheets and held in upright position by suitable sliding weights 167, see Fig. 19, one extreme edge of the folded sheet is forced beyond a short lip 168 of a detaining plate 169 secured to the inner side of table 142 by set screws 170, see Figs. 19 and 21. A return or back movement of push-plate 164 then occurs prior to discharge of another folded sheet and in this return the sheet last stacked is prevented from opening at its open folded ends or edges by lip 168. Its return is also prevented by a series of upwardly extending strips 171 pivotally secured to the table bottom and held in upwardly projecting relation to the sheets by leaf springs 172, 130

see Fig. 22. Obviously, when a folded sheet is moved forward these strips 171 are depressed. Telescoping of one folded sheet into a sheet previously discharged upon table 142 is prevented by a pivoted deflector plate 173 pivotally mounted upon a slide 175 which is dovetailed in the channel of push-plate 164 and is adapted to be moved transversely of the table relatively as near to discharge rolls as may be desired to effectively prevent spreading of the open or free edges of the folded sheet if lip 168 fails of its purpose. A leaf spring 174 secured in slide 175 engages deflector 173 to force it outward and this spring is a light spring which readily yields when a folded sheet is discharged from rollers 102 and 103 against deflector 173. A finger or stop 180 is also slidably mounted in channeled push-plate 164 to limit the outward movement of the folded product when discharged upon table 142, see Figs. 17 and 19.

Slide 175 is square in shape and beveled alike at all four edges, so that the same may be inserted in the push-plate channel either in the position shown in Fig. 21 or at right angles thereto which will place the pivot end of deflector 173 uppermost with the body of the deflector plate inclined forwardly and downwardly in respect to the top face of table 142 as shown in Fig. 23. This latter position of the parts is necessary when the folded product is discharged downwardly instead of laterally, although the function of the deflector is unchanged as it serves in both instances to keep the folded sheet from opening after it is banked on table 142.

Parallel folds.—When parallel folds are made, frame 97 is rotatably set transversely of the machine with the rollers thereof in parallel line with horizontal slot 7. The finished product is then discharged downwardly instead of laterally and although only a six-page and eight-page parallel fold is shown in diagrammatic views, Figs. 6 and 7, respectively, it will be understood that four, ten, twelve and sixteen page parallel folds can also be made as well as other folds not so commonly used. In stacking sheets having parallel folds, either stacker may be used but selection thereof is dependent upon whether initial feed to the first folding blade is either to the right or the left of the longitudinal center of the machine. If folding operations upon the sheet proceed with initial feed of the paper more or less centrally of the machine both stacking devices may be used, particularly if the sheets are wide, say the full width of the machine. This is possible because both stacking tables may be brought to the same horizontal plane and because the drive mechanism of both stackers are operatively driven in unison.

Stacker control.—There are occasions,

however, when it is desirable to stop stacking operations and again when it is necessary to differently time the active participation of push-plate 164 with the discharge rollers, particularly as said rollers run at a constant speed but deliver sheets of different widths or lengths. To this end bevel gear 146 on countershaft 148 has a ratchet hub which interlocks with a slidable ratchet collar 177 adapted to be rotated by pin 178 secured to said shaft and locked against end movement by screw nut 179. Bevel gear 146 is free to rotate on said shaft when collar 177 is released therefrom. Any suitable device which will permit a disconnection or change in timing operations for the stackers may be used at this point or elsewhere in the line of the drive connections.

In Fig. 23 a modification in the arrangement of upper plate 3 may be noted, the said plate at the feed end of the machine being inclined to facilitate feeding operations.

In Fig. 24 a plate 181 is shown with a curved upper edge to deflect a sheet having a single fold into the bite of rollers 95 and 96 and thence against deflector 110 and out between feed rollers 96 and 101 without further fold. Plate 181 may be a separate attachment, or stop plates 32 may be constructed and used for this purpose.

It is not deemed necessary to describe all the folds adapted to be made by this machine, as it is obvious that many different kinds of folds can be made by presenting the sheets variously in respect to the slots in the central plate 4 and in respect to the various folding blades as well as by setting the various gage-stops in different positions and by rotatable adjustment of blade 9 and frame 97.

The variously folded sheets herein referred to and represented by Figs. 2 to 7, inclusive are further designated as sheets A, B, C, D, E and F, running consecutively with the said figures, and Fig. 2, sheet A, has a single transverse fold at its middle, while sheet B is folded at right angles through its center lengthwise and longitudinally. Fig. 4, sheet C, has a single transverse fold and two longitudinal folds dividing the same into three different subdivisions. Fig. 5, sheet D, shows three transverse folds and one longitudinal fold. Fig. 6 has two transverse folds equal distances from its ends, and Fig. 7 has three folds transversely, the folds in all said sheets being indicated by dotted lines.

What we claim is:

1. In a paper folding machine, a feed table having a slot and a reciprocating folding blade in line with said slot, feed rollers on one side of said blade and a stop-gage on the other side thereof, and a paper buckling device on said table between said rollers and the blade.

2. In a paper folding machine, a feed roller and an oscillating support therefor, a buckling deflector for the paper next behind said feed roller, a reciprocating folding device for the paper, and adjustable means to limit feed of the paper beyond said device.
3. In a paper folding machine, a folding device and a guideway for the folded product comprising a slotted plate and a hinged frame and rollers between said parts, in combination with a reciprocating folding frame rotatably mounted at right angles to said guideway.
4. In a paper folding machine, a folding blade and a guideway opposite thereto, rollers in said guideway, a pair of swinging frames for said rollers, and a second folding blade mounted to operate between said pair of frames.
5. In a paper folding machine, a folding device and a guideway opposite thereto, in combination with a second folding device mounted at right angles to said guideway to produce a second fold at right angles to the first, and means to cause second-fold operations to proceed initially at the previously folded edge of the sheet.
6. In a paper folding machine, a guideway for the paper and folding devices on either side thereof having means to independently adjust the same on parallel or inclined lines relatively to each other and to said guideway.
7. In a paper folding machine, a folding device, a swinging frame having paper feed rollers mounted thereon opposite said device, and means to adjust said frame variably on inclined lines in respect to said device.
8. In a paper folding machine, a guideway for the paper, and a folding blade adjustable to either parallel or inclined folding positions relatively to said guideway and rotatably mounted to permit adjustment to varying folding positions at right angles to said guideway, in combination with fold and feed mechanism coöperating with said blade on the opposite side of said guideway.
9. A paper folding machine having means to produce a single fold, in combination with a device adapted to produce a second fold parallel with or at an angle to the first fold, said device being adjustable to produce the angular folds by initial engagement at the previously folded edge of the sheet.
10. In a paper folding machine, a paper guideway, reciprocating folding blades adapted to operate successively and separately and having rotatable supports for each, a paper deflector adjustably mounted upon one of said blades, and rollers to form finished folds.
11. In a paper folding machine, a folding device comprising a reciprocating blade and a slotted guideway, in combination with a series of feed and finishing rolls, a second reciprocating blade, a gage-stop for the paper, a deflector, and means to adjust said second blade and deflector for shunting the paper sheet through said rollers without further fold.
12. In a paper folding machine, a main frame and a cross-head pivotally mounted thereon, a rotary frame journaled in said cross-head, a series of rollers and a reciprocating folding blade mounted upon said rotary frame, and power connections for said rollers and blade permitting independent rotation of said rotary frame and swinging of said cross-head within said main frame.
13. In a paper folding machine, a main frame and a cross shaft therein, a cross-head journaled to swing on said shaft, an adjustable device to secure said cross-head in any adjusted position and a rotatable frame journaled in said cross-head, in combination with a folding device mounted upon the main frame, folding mechanism mounted upon said rotatable frame, and power connections for said folding device and folding mechanism.
14. In a paper folding machine, a blade to produce a single fold, a guide-way for the folded sheet, a vertically adjustable guide stop for the folded sheet, laterally adjustable guide-strips within said guide-way, and means to reciprocate one of said guide-strips to jog the paper, in combination with means to produce a second fold.
15. In a paper folding machine, a guideway for the paper, opposed rollers in said guideway, vertical guide strips between said rollers, guide-stops at the bottom of said guideway, and paper retainers adjustably mounted on said guide-stop.
16. In a paper folding machine, a guideway comprising a plate having bisecting slots therethrough, and a swinging frame at either side of one of said slots having a series of shafts and rollers adjustably mounted on said shafts, in combination with a folding blade adapted to enter either of said slots.
17. In a paper folding machine, a rotatable folding mechanism adapted to be adjustably set in different positions, in combination with a set of stacking devices adapted to be adjustably set to receive the folded product in any of the adjusted positions of said rotatable folding mechanism.
18. In a paper folding machine, a rotatable frame having folding and discharge devices for the paper and adapted to be adjusted to discharge the folded product either to the left or to the right or below the axial center of rotation of said frame, in combination with stackers adjustably mounted to coöperate with said discharge devices in all

the different positions of the rotatable frame.

19. In a paper folding machine, a rotatable frame and folding devices mounted thereon having power connections permitting rotation of said frame, in combination with stacking devices having power connections and adjustable timing and throw-out connections and being movably mounted in respect to said rotatable frame to permit rotation thereof and to give adjustable set positions in respect thereto in all of its different working positions.

20. In a paper folding machine, a plurality of folding devices adapted to make a plurality of folded paper sheets, one of said devices being mounted upon a rotatable frame in respect to another folding device, in combination with a stacking device vertically adjustable to receive the folded product thereon from either its side or top dependent upon the position of said rotatable frame.

21. In a paper folding machine, a guide-way comprising a plate having bisecting slots, a reciprocating blade adjustably mounted in respect thereto, and means co-

operating with said blade and guide-way to finish and discharge the folded product, said means being rotatably adjustable, in combination with stacking means adjustably mounted in respect to said rotatable means to receive and stack the folded product in all of the different delivery positions.

22. In a paper folding machine, a vertically reciprocating folding blade, a slotted guideway, a horizontally reciprocating blade, a rotatable frame mounted on a horizontal axis in alignment with said horizontally reciprocating blade, and a third reciprocating blade and feed and finishing rollers carried by said rotatable frame, in combination with stacking devices adjustably mounted in respect to said rotatable frame to permit adjustments thereof and to set the same for co-operation with the rollers in all of their different discharge positions.

In testimony whereof we affix our signatures in the presence of two witnesses.
